UNITED STATES PATENT OFFICE.

WILLIAM R. LEE, OF ROCHESTER, NEW YORK.

ARCH-SUPPORT.

976,888.

Specification of Letters Patent. Patented Nov. 29, 1910.

Application filed November 22, 1909. Serial No. 529,328.

To all whom it may concern:

Be it known that I, WILLIAM R. LEE, of Rochester, in the county of Monroe and State of New York, have invented certain 5 new and useful Improvements in Arch-Supports; and I do hereby declare the following to be a full, clear, and exact description of the same, reference being had to the accompanying drawings, forming a part of 10 this specification, and to the reference numerals marked thereon.

The present invention relates to a support adapted to be inserted within a shoe for the purpose of preventing strains on the 15 arch of a human foot, and an object of this invention is to provide a construction which may be adapted to the individual needs of a wearer by providing a height increasing member which may be easily removed but 20 when in proper position will be securely retained against displacement.

To these and other ends the invention consists in certain improvements and combinations of parts all as will be hereinafter 25 more fully described, the novel features being pointed out in the claims at the end of the specification.

In the drawings: Figure 1 is a plan view of the arch support constructed in accordance with this invention; Fig. 2 is a section 30 on the line *a—a* of Fig. 1; Fig. 3 is a section on the line *b—b* of Fig. 1, and Fig. 4 is a detail view of one of the height increasing members.

The arch support comprises preferably 35 two layers 1 and 2 of sheet material secured together by stitches 3 or other suitable means along the greater portion of their edges, the inner side preferably being left unstitched 40 in order to provide a pocket 4 which opens at the inner side of the support to receive a suitable height increasing member 5. This height increasing member may be of any suitable form and material, but it is preferably 45 wedge-shaped and made of yielding material, such as felt, and the thickness or height of the member varies with the individual needs of the user.

In order to prevent accidental displacement 50 of the height increasing member and at the same time to permit the latter to be readily inserted or removed, one of the parts of the device, in this instance the main sup-

port, is provided with a flexible tongue 6 adapted to be inserted through a slit 7 55 formed in the other part. Preferably this tongue is formed by cutting the material of the upper wall of the pocket, thus providing an opening 8 which permits the tongue to be manipulated from the exterior 60 of the support and introduced into the slit 7 of the height increasing member 5. The tongue preferably extends in a direction away from the opening of the pocket so that any tendency of the member 5 to move in the 65 direction of the pocket opening is resisted as the tongue will then move farther into the slit in the member 5. Of course, to remove the member 5 the tongue must first be withdrawn from the slit and this is done by 70 manipulating the tongue through the opening 8.

An arch support constructed in accordance with this invention permits the wearer to obtain a height for the support corresponding to his individual needs and desires. The adjustment of the support is 75 quickly and easily obtained and there is no liability of the height increasing member accidentally shifting to an undesirable 80 position. The construction by which these results are obtained is simple to operate and is inexpensive to manufacture.

I claim as my invention:

1. An insertible arch support for shoes 85 having a pocket therein opening at one edge of the support, a flexible finger being provided on a wall of the pocket and projecting in a direction away from the opening.

2. An insertible arch support for shoes 90 formed of two pieces of sheet material secured together along the greater portion of their edges and separated along the other portion to provide a pocket between them, one wall of the pocket being provided with 95 a flexible finger cut from one of the pieces of sheet material.

3. An insertible arch support for shoes having a pocket therein opening at one edge of the support, the upper wall of the pocket 100 being provided with an opening and with a flexible finger operable through said opening to secure a height increasing member in the pocket.

4. An insertible arch support for shoes 105 having a pocket therein opening at one edge

of the support, the upper wall of the pocket being provided with an opening and with a flexible finger operable through said opening and extending in a direction away from the opening of the pocket, combined with a height increasing member having a slit therein into which the finger is adapted to

be inserted to retain said member in the pocket.

WILLIAM R. LEE.
